Fig. 1.

Fig. 2.

Fig. 3.

To all whom it may concern:

Be it known that I, Warren W. Champion, a citizen of the United States of America, residing at Springdale, Hamilton County, State of Ohio, have invented a new, original, and ornamental Design for a Bottle, of which the following is a specification, reference being had to the accompanying drawing, forming a part hereof.

In the drawing:

Figure 1 is a view in elevation of one face of a bottle showing my new design, the opposite face of the bottle being the same;

Fig. 2 is a view in elevation of one side of the bottle, the opposite side being the same; and

Fig. 3 is a view in section taken along the line III-III in Fig. 1.

I claim:

The ornamental design for a bottle, as shown and described.
